US0D1051999S

(12) **United States Design Patent** (10) Patent No.: **US D1,051,999 S**
(45) Date of Patent: ** Nov. 19, 2024

(54) **SCOOTER**

(71) Applicant: **RAZOR USA LLC**, Cerritos, CA (US)

(72) Inventors: **Ian Desberg**, Cerritos, CA (US); **Nari Cho**, Cerritos, CA (US)

(73) Assignee: **RAZOR USA LLC**, Cerritos, CA (US)

(**) Term: **15 Years**

(21) Appl. No.: **29/692,708**

(22) Filed: **May 28, 2019**

(51) LOC (14) Cl. **21-01**

(52) U.S. Cl.

USPC **D21/423**

(58) **Field of Classification Search**

USPC D21/419, 421, 423, 426-428, 435, 760,

D21/765, 771; D12/1, 8, 108, 112, 113

CPC . B62K 3/002; B62K 9/00; B62K 9/02; B62K

13/00; B62K 2202/00

(57) **CLAIM**

The ornamental design for a scooter, as shown and described.

DESCRIPTION

FIG. 1 is a front, top, and left side perspective view of an embodiment of a scooter of our design;

FIG. 2 is a left side view thereof;

FIG. 3 is a right side view thereof;

FIG. 4 is a top view thereof;

FIG. 5 is a bottom view thereof;

FIG. 6 is a front view thereof;

FIG. 7 is a rear view thereof; and,

FIG. 8 is a rear, top, and right side perspective view thereof.

The broken lines are for the purpose of illustrating portions of the article that form no part of the claimed design.

1 Claim, 6 Drawing Sheets

US D1,051,999 S
